FENDER

Ivan M. Kirlin, Detroit, Mich.

Application September 27, 1937, Serial No. 165,858

2 Claims. (Cl. 114—219)

This invention relates to the construction of an improved pneumatic boat fender, which is capable of resisting tremendous strains, yet extremely light in weight and easy to handle. An object of the invention is to provide an improved boat fender which, in addition to possessing the advantages mentioned, is incapable of marring the finish of boats or fittings by abrading the same. Another object is to provide such a fender which may be stored very compactly, and which in addition constitutes a permanently buoyant life preserver.

Still another object is the provision, in conjunction with such a fender, of improved elastic supporting means, so arranged as to prevent injury to the fender, or to the line by which it is attached to a vessel, due to rocking of the latter while against a dock or wharf, and while the fender is trapped between the vessel and the dock. Still another object comprises the provision of improved means for suspending such fenders.

Another object comprises the provision of an improved pneumatic fender construction provided with an inflating valve so positioned as to be guarded at all times against injury.

Another object is the provision of such a fender which is of very simple and inexpensive construction.

30 In the drawing:

Figure 1 is a side elevational view of a fender constructed in accordance with the principles of this invention, showing the manner of suspension thereof.

35 Figure 2 is a longitudinal and substantially diametric cross section, and

Figure 3 is a transverse sectional view, taken substantially on the line 3—3 of Figure 1, and looking in the direction of the arrows.

40 Referring now to the drawing, and more particularly to Figure 2, it will be seen that the main casing of the device comprises a tubular or cylindrical fabric element 10, which may be of canvas or the like, and reinforced or otherwise in accordance with the stresses which the device is to withstand. For this purpose ordinary fire hose, of large diameter, serves very well, the hose being cut into suitable lengths, and the ends drawn in and reinforced by annular ring-like 45 reinforcing members 12, over which the material is folded, as shown in Figure 2, such arrangement providing constricted ends with axial openings of reduced size, the openings being bounded by marginal beads. At one end the opening or mouth 50 of the casing is closed, and tightly held between

inner and outer washers 14, 15, respectively, clamped against opposite sides of the beads by a bolt 17, and a nut 18 threaded upon the outer extremity thereof at the end of the casing. The bolt carries a swingable supporting bail 20. Similar clamping washers, 25—26, close the other end of the casing, such washers, however, having larger openings therein to permit the valve stem 32 to project therethrough. The valve stem is sealed to the bladder 35 to enable inflating and deflating the same. The clamping bolt for washer portions 25—26 may consist of an integral hollow stem portion 25A, carried by washer 25 and having a threaded extremity upon which is screwed the clamping nut 28. A swinging bail 30 is also pivoted to the nut 28. A conventional air check valve 36 and valve cap 38 may be carried by stem 32.

20 Supporting straps 40 are sewn or otherwise secured to one end of the casing 10, at diametrically opposite points. The straps are joined at a central point above the bail 20, and at said point also secured to a third strap 41 attached to the bail, the fender being thus suspended at three points. An extension 42 of the three straps is connected to a spring element 44, which may comprise either metal or elastic rubber, provided at its top with a ring 45 or other suitable attaching means for the supporting line 50. I have found that elastic rubber reinforced with fabric webbing, of the character used for shock absorbers for aircraft, makes a very satisfactory body for the elastic element 44.

25 Over the exterior of the casing 10 is preferably fitted another cylindrical casing 11, which extends throughout that portion of the length of the casing which is of full diameter. The outer reinforcing tubular section 11 is preferably secured to the casing section 10, either by sewing or cementing, and is provided at its ends with 30 folded reinforcing seams 13.

35 When the device is inflated, and suspended in the manner shown in Figure 1, it may be interposed between a vessel and a wharf, to prevent contact between them, and its resistance increases greatly with compression. Due to the 40 ability of the elastic suspending member 44 to stretch, when the wharf tends to hold the fender against movement with the boat, as the latter rocks, no undue stress is imposed either upon the suspending line or the fender, both thereof being 45 thus protected against injury.

45 While it will be apparent that the illustrated embodiment of my invention herein disclosed is well calculated to adequately fulfill the objects 50

and advantages primarily stated, it is to be understood that the invention is susceptible to variation, modification and change within the spirit and scope of the subjoined claims.

5 5 What I claim is:

1. A fender for boats and the like comprising a substantially cylindrical, flexible but inelastic fabric casing, means constricting and securely closing the ends thereof, including a closure element at one end of said casing having an aperture

therethrough, a separate inflatable bladder within said casing, inflating means for said bladder extending through said aperture, and means unattached to the bladder for supporting the casing.

2. Means as set forth in claim 1 in which at least a part of said supporting means extends upon opposite sides of said inflating means and comprising guard means to protect the same.
